(57) **CLAIM**

The ornamental design for a loader machine, as shown and described.

DESCRIPTION

FIG. 1 is a right front perspective view of a loader machine showing our new design.

FIG. 2 is a left rear perspective view thereof.

FIG. 3 is a right side elevational view thereof.

FIG. 4 is a left side elevational view thereof.

FIG. 5 is a front elevational view thereof.

FIG. 6 is a rear elevational view thereof; and,

FIG. 7 is a top plan view thereof.

The broken line showing of the windshield wiper, the engine cover formations, the bucket, and the treads throughout is included for the purpose of illustrating environmental structure and forms no part of the claimed design.
